T. J. STURTEVANT.
JARRING MECHANISM FOR SCREENING OR SEPARATING MACHINES.
APPLICATION FILED JAN. 10, 1917.
1,229,821. Patented June 12, 1917.

UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

JARRING MECHANISM FOR SCREENING OR SEPARATING MACHINES.

1,229,821.

Specification of Letters Patent. Patented June 12, 1917.

Application filed January 10, 1917. Serial No. 141,589.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Jarring Mechanisms for Screening or Separating Machines, of which the following is a specification, reference being had therein to the accompanying drawing.

This invention relates to that class of inclined screening or separating machines in which the screens are percussively jarred or 15 vibrated, and the invention relates more particularly to certain improvements in the machine of the Bell and Sturtevant Patent No. 923,108, dated May 25, 1909, in which the screens are jarred from hammers or 20 strikers arranged below the screens. The present improvement has special reference to the hammer or vibrating mechanism for percussively jarring the fine screens of the separators.

25 In accordance with the present invention the fine screen is percussively jarred from below by means of hinged hammers carried by revolving disks, said hammers striking at intervals on plates interposed between 30 said hammers and yieldingly-mounted pins connected with elastic diaphragms which yieldingly support impact bars which, in turn, yieldingly sustain the screen or screens to be jarred.

35 The accompanying drawing is a detail view illustrating one of the improved jarring devices, a plurality of which will of course be used in each separating machine for jarring the screen or screens.

40 Referring to the drawing, 12 denotes the bottom part of the separator casing to which are attached hangers 13 and 14. A revolving shaft 15, which will have its bearings in a plurality of hangers 13, is provided 45 with disks 16 to which are hinged or pivoted hammers 17. Supported by the hanger 14 is a spring 18 having attached to its free end a protecting impact plate 19 to be struck by the hammers 17. Resting at its lower 50 end on the impact plate 19 is a pin 20 attached to a sleeve 21 which is in turn se-

cured to an elastic diaphragm 22 mounted on the bottom casing part 12. Attached to the upper side of the said diaphragm 22 is a socket 23 loosely receiving the lower end 55 of an impact bar 24, the upper end of which is loosely received by a socket 25 on which rests a transverse protection plate 26 secured to the wire mesh screen 27, so that said screen will be elastically or resiliently supported by diaphragms 22.

It will be understood that a series of these screen-supporting and jarring mechanisms, only a single one of which is illustrated in the drawing, will be provided, as is common 65 in vibrating separators of the class to which this invention relates.

I do not herein claim broadly the elastic diaphragms from which the screen to be jarred is yieldingly supported through the 70 impact bars or pins, as this feature is shown in my application No. 141,182, filed January 8, 1917.

Nor do I herein claim broadly revolving hammers, acting from below on impact bars 75 or pins which support the screen and which hammers are carried by rotating disks, as this feature is claimed in my application No. 141,588, filed simultaneously herewith.

Having thus described my invention I 80 claim and desire to secure by Letters Patent:

1. In a separator, the combination with a casing part provided with elastic diaphragms, of pins connected with said diaphragms, revolving hammers for acting on said pins, springs connected with said casing part and provided with impact plates interposed between said pins and hammers, impact bars sustained by said diaphragms, 90 and a screen elastically supported from said diaphragms through said impact bars.

2. In a separator, the combination with a casing part provided with elastic diaphragms, of pins connected with said diaphragms, revolving hammers for acting on said pins, rotating disks by which said hammers are carried and to which they are hinged or pivoted, springs connected with said casing part and provided with impact 100 plates interposed between said pins and hammers, impact bars sustained by said dia-

phragms, and a screen elastically supported from said diaphragms through said impact bars.

3. In a separator, the combination with an 5 elastically supported screen, of hammers, acting from below, for jarring said screen, devices loosely mounted relative to said

screen, and through which the impact of said hammers is to be transmitted to said screen, and impact members interposed between said devices and said hammers.

In testimony whereof I affix my signature.

THOMAS JOSEPH STURTEVANT.
